UNITED STATES PATENT OFFICE

125,621

DESIGN FOR A HAT STAND OR SIMILAR ARTICLE

Hortense B. Hewitt, New York, N. Y.

Application November 30, 1940, Serial No. 96,963

Term of patent 3½ years

To all whom it may concern:

Be it known that Hortense B. Hewitt, a citizen of the United States and resident of New York city, in the county of New York, State of New York, has invented a new, original, and ornamental Design for a Hat Stand or Similar Article, of which the following is a specification, reference being had to the accompanying drawing, forming part thereof, and in which,

The single figure of the drawing is a perspective view of a hat stand, embodying my new design.

I claim:

The ornamental design for a hat stand or similar article, substantially as shown.

HORTENSE B. HEWITT.
